UNITED STATES PATENT OFFICE.

PETER J. SHRUM, OF MONACA HEIGHTS, AND HAROLD A. HENIGEN, OF ROCHESTER, PENNSYLVANIA, ASSIGNEES TO COLONA MANUFACTURING COMPANY, OF PITTSBURGH, PENNSYLVANIA, A CORPORATION OF PENNSYLVANIA.

THREAD PROTECTOR.

Original application filed July 15, 1922, Serial No. 575,167. Divided and this application filed June 29, 1923. Serial No. 648,493.

Our invention consists in an improvement in thread protectors and has for its object to provide a device of this class formed of a continuous integral ring provided with 5 interior securing threads, a terminal retaining annular lip or flange, and an opposite outwardly extended terminal coping or protecting portion, as shall be more fully hereinafter described.

10 The device is formed preferably from a section of tubing, either seamless or welded, by the operation forming the subject matter of a prior patent of Harold A. Henigen and myself, No. 1,475,032, of which this application is a division.

The device is illustrated in the accompanying drawing, in which:

Fig. 1 is a longitudinal sectional view through the threaded end portion of a pipe 20 provided with a protector as applied;

Fig. 2, an outer end view of the protector; and

Fig. 3, an enlarged sectional detail view showing the device as applied and of substantially full size.

The main body portion of the protector is composed of a cylindrical blank formed in the manner and by the means disclosed in the prior application above referred to, or 30 in any other suitable manner providing an inwardly swaged thickened middle portion for threading. The middle section 2 of the protector constitutes the attaching or engaging portion of the device having the series 35 of threads 3 for engagement with the threads of a pipe 4 or other article to be protected. Threads 3 extend for sufficient length longitudinally of the middle portion of the protector for firm connection, by 40 screwing, and throughout substantially the thickened portion of the device, when the blank is made by the method of inward swaging of said application.

The outer end portion of the device is 45 outwardly enlarged peripherally by a laterally extending bulbous rounded ring 5 spaced away beyond the zone of threads 3 and providing an interior clearance or non-attaching space 6. Rounded portion 5 is

turned abruptly inwardly beyond the 50 threaded zone, providing the terminal annular lip or edge 7, adapted to abut against the outer end of pipe 4, when screwed up tight, as shown.

Ring 5, which is the portion of the protector of largest outside diameter, provides 55 an annular outer bearing which completely surrounds and protects the outer threaded portion of the pipe, and by which it may be rolled or subjected to the rough handling 60 of shipment, storage, etc. without injuring the threads. The other end of the protector is laterally larger than the middle threaded section sufficient to leave a clearance space 65 between its inner unthreaded surface and the pipe threads. As thus made, the laterally larger inner end portion 9 extends beyond the attaching portion, in the manner of a skirt or sleeve which projects over or beyond the innermost threaded portion 70 of the pipe, completely protecting such threads from injury at all times.

The inside diameter of the distal end or mouth of the skirt 9 is materially greater than the inside diameter of the pipe, so that 75 the protector may be readily slipped over the end of the pipe preliminary to screwing the protector onto the threads.

In construction, the device is formed in any suitable manner, as by swaging, from 80 a cylindrical ring blank, to form the middle contracted thickened portion and the enlarged end portions, with the inwardly turned retaining lip.

The middle section is then tapped to cut 85 the threads 3 of suitable size for intended use, when the protector is ready for screwing on the pipe to be protected.

By reason of its annular reinforcing enlargements, we are enabled to make the protector of metal of minimum gauge or thickness, due to its added bracing strength, and with corresponding economy. The device may be made in any desired size or dimensions; it is very strong and durable, well 90 adapted to the purpose in view, and capable of repeated use. It may be made in different proportions from those shown, or changed in 95

detail construction by the skilled mechanic, but all such changes are to be considered as within the scope of the following claims.

What we claim is:

- 5 1. A thread protector consisting of a single continuous metallic sleeve having an intermediate cylindrical thickened interiorly threaded portion of reduced diameter, a skirt at one end of said threaded portion
10 adapted to extend over threads to be protected and out of engagement therewith, said skirt having an inside diameter which is materially greater than that of the outside diameter of the threads to be protected there-
15 by and the inside diameter of the mouth of the skirt being of sufficiently greater diameter than the outside diameter of the threaded article to be protected to permit the skirt of the protector to be readily slipped over the end of such article preliminary to screwing it onto the threads, and an outwardly flared terminal portion at the other end of the intermediate portion terminating in an inturned flange adapted to form a protection for the end of the threaded article to which the protector is applied.
- 20 2. A pipe thread protector consisting of a metallic sleeve having an interiorly threaded intermediate cylindrical portion adapted to be screwed onto and protect the intermediate portion of the pipe threads to be protected, a skirt at one end of said threaded portion adapted to extend over threads to be pro-

tected and out of engagement therewith and having an inside diameter at its mouth 35 which is materially greater than the outside diameter of the pipe whereby the skirt of the protector may be readily applied over the end of the pipe preliminary to screwing the protector onto the threads, and an outwardly flared terminal portion at the other end of the intermediate portion terminating in an inturned flange adapted to form a protection for the end of pipe to which the protector is applied.

40 45 3. A one-piece thread protector formed from a section of tubing and having an intermediate cylindrical portion provided with a plurality of screw threads formed on the interior thereof, said tubing at one end being unthreaded and flared to form a skirt adapted to extend over and out of contact with threads to be protected, the inside diameter of the mouth of the skirt being sufficient to permit the same to be readily slipped over the end of the threaded article to be protected preliminary to screwing it onto the threads of the article, said tubing at the opposite end from said skirt being bulged outwardly and then turned inwardly to form 50 55 a stop for contact with the end of the article to be protected.

55 60 In testimony whereof we hereunto affix our signatures.

PETER J. SHRUM.
HAROLD A. HENIGEN.
